Martin O'Marra Inventor

UNITED STATES PATENT OFFICE.

MARTIN O'MARRA, OF KINGSTON, NEW YORK.

BOLTLESS RAIL-FASTENER.

No. 920,383.

Specification of Letters Patent.

Patented May 4, 1909.

Application filed August 21, 1907. Serial No. 389,586.

To all whom it may concern:

Be it known that I, MARTIN O'MARRA, a citizen of the United States, residing at Kingston, in the county of Ulster and State 5 of New York, have invented a new and useful Improvement in Boltless Rail-Fasteners, of which the following is a specification.

This invention is a novel form of rail fastening device the object being to provide an 10 exceedingly cheap, simple and efficient form of fastener which will completely avoid the use of nuts and bolts and also dispense with the use of fish-plates, chairs and similar appliances.

Another object of the invention is to provide a novel form of rail fastener which is 15 particularly adapted for use in connection with metallic ties.

Another object is to provide a fastener 20 which can be quickly and easily applied and disconnected.

With these various objects in view my invention consists essentially in the employment of a base-plate having a spring clamping plate connected thereto, said base plate being adapted to rest upon the top surface of 25 the metal cross-tie, and means for binding the clamping plate firmly upon the base of the rail.

The invention consists also in certain features of construction and novelties of combination, all of which will be hereinafter fully described and pointed out in the claims.

In the drawings forming a part of this 35 specification:—Figure 1 is a sectional elevation showing my improved form of boltless rail fastener applied. Fig. 2 is a top plan view of the same. Fig. 3 is a section on the line 3—3 of Fig. 2. Fig. 4 is a view of the 40 base and clamping plate. Fig. 5 is a detail perspective view of the keeper. Fig. 6 is a top plan view showing a slight modification. Fig. 7 is a longitudinal section on the line 45 7—7 of Fig. 6. Fig. 8 is a modified form of the combined base and clamping plate. Fig. 9 is the modified form of the keeper.

Referring to the drawings A indicates an ordinary railroad rail and B the usual construction of metallic cross-tie.

In practice I prefer to construct my fastening device in such a manner that the base-plate will perform the function of a rail-chair and brace, and I therefore construct the base-plates C with the upturned end C', 55 against which the base of the rail bears, as most clearly shown in Fig. 1, and this bear-

ing end or flange is substantially the same width as the metallic rail tie which is usually about eight inches. At the opposite end of the base-plate is formed a depending bend 60 D, the continuation of which is the clamping-plate E. The combined base and clamping plates are formed of stout spring metal, and the depending bend D is adapted to be inserted in a transverse slot D' produced in 65 the top of the metal tie and this securely holds the fastening device firmly in place and prevents any possibility of the rails spreading or creeping. Now, when the rail is seated upon the base-plate against the end or 70 flange C', a lever is employed to force the clamping plate down upon the base of the rail as most clearly shown in Fig. 1, and in order to hold the clamping plate in this position, I employ a keeper F which is in the 75 form of an open loop, having the inwardly projecting ends F' which are inserted in the oblique slots B² and forced downwardly until they reach the recesses B³ cut in the sides of the cross-tie, and this keeper being thus securely locked in position upon the cross-tie, and straddling the clamping-plate, will 80 securely hold said plate in its depressed position, and in that manner securely fastens the rail to the metal tie, and this without the use 85 of bolts or nuts and it will be readily understood that all danger of the rail spreading or creeping is entirely avoided.

In Figs. 6 to 9 I have shown a slightly modified form of device which is constructed 90 with the view of economizing in metal, and it will be noted that the base plate C is made considerably shorter and is provided with a downwardly extending lip C² which enters a transverse slot C³ produced in the top of the 95 cross-tie. The depending bend and clamping plate are exactly the same. The keeper, however is constructed slightly different, being provided with outwardly projecting ends F², which are adapted to be passed through 100 openings F³ produced in the top of the cross-tie and leading from these openings F³ are the longitudinal slots F⁴ in which the side members of the keeper slide, when the said keeper is moved up on the clamping plate 105 for the purpose of binding said clamping plate to the rail.

A rail fastener constructed as herein shown and described is particularly useful upon curves as all danger of the rail spreading or 110 creeping is avoided.

Having thus fully described my invention,

what I claim as new and desire to secure by Letters Patent is:—

1. The combination with a railroad rail, of a base plate provided with means to prevent lateral movement of the rail thereon, a clamping plate integral with the base plate and a keeper embracing said plate and detachably connected with the metallic cross tie.
- 10 2. In a device of the kind described, the combination with the slotted cross-tie, of the base-plate having a flange at one end and a depending bend at the other end, the clamping plate integral with the base-plate and extending upwardly from the depending bend, and the keeper having its ends shaped for engagement with the slotted cross-tie, the body of said keeper being adapted to straddle the base and clamping plates and

hold them in position in conjunction with a rail, all of said parts being constructed and arranged substantially as shown and described.

3. The combination with a rail tie and rail, of a base plate adapted to embrace the base of the rail at one end, the opposite end of said base plate being provided with means to prevent lateral movement of the rail, a clamping plate adapted to engage the rail, said clamping plate being held against lateral movement on the tie, and means for engaging the tie and drawing the plates toward the tie substantially as shown and described.

MARTIN O'MARRA.
